Primary Examiner — Mitchell I. Siegel*Assistant Examiner* — Jasmine L. Comedy(74) *Attorney, Agent, or Firm* — Connie R. Masters(57) **CLAIM**

The ornamental design for a wall or surface covering as shown and described.

DESCRIPTION

FIG. 1 is a bottom perspective view of a wall or surface covering, showing my new design;

FIG. 2 is a bottom view thereof;

FIG. 3 is a front view thereof;

FIG. 4 is a back view thereof;

FIG. 5 is a left side view thereof;

FIG. 6 is a right side view thereof; and

FIG. 7 is a top view thereof; and,

FIG. 8 is a cut view thereof, which is taken from view line 8 of FIG. 1.

The broken lines depict portions of the wall or surface covering that form no part of the claimed design. The line-dot-line broken lines indicate boundary lines of the claimed portions and from no part of the claimed design.
